UNITED STATES PATENT OFFICE.

JOHN DEMETRIUS POLETIS, OF DETROIT, MICHIGAN.

BUTTER REFRIGERATOR.

Application filed April 19, 1926. Serial No. 103,011.

The present invention relates to butter refrigerators especially adapted for use in hotels, lunch rooms, etc. and its primary object is to preserve the butter in a relatively 5 solid and sanitary condition at all times.

Another object of this invention is to provide a refrigerator insulated in an especial manner and so formed that a cooling agent, such as ice, is employed to effectively cool the 10 butter without coming in contact therewith.

A further object of the invention is to provide a butter refrigerator in which the butter carrying drawers are so arranged that they do not come in contact with the refrigerator 15 but are spaced therefrom at all points so as to permit free and uninterrupted circulation of air around the drawers.

Other objects of the invention will be apparent from the following description of the 20 present preferred form of the invention taken in conjunction with the accompanying drawings, wherein:—

Fig. 1 is a front elevational view of a butter refrigerator constructed in accordance 25 with the present invention;

Fig. 2 is a vertical sectional view thereof; and

Fig. 3 is a horizontal sectional view taken 30 on the line 3—3 of Fig. 1 looking in the direction of the arrows.

The refrigerator constructed in accordance with the present invention consists of a cabinet 4 which may be of any desired shape and size and constructed from any suitable 35 material. The cabinet is preferably supported by legs 5 in order to space the cabinet from the floor or other supporting base. The cabinet includes an inner shell 6 preferably made of metal and spaced from the inner faces of the outer shell so as to accommodate 40 an insulating material 7 composed of cork or the like. The front end of the inner shell 6 is cut away for a purpose hereinafter set forth. A pair of partitions 8 are mounted in the inner shell the rear marginal edge of 45 each of which abuts the inner wall of the shell 6 while the outer marginal edge engages the inner face of the body or outer shell of the cabinet. The lower marginal edge of each of 50 the partitions is snugly engaged with the bottom of the inner shell. In this way compartments 9 are provided adapted for the reception of a cooling agent, such as ice. Each 55 of these compartments is provided with a suitable closure 10. It will be noted that each of the partitions 8 is provided at its lower end

with an opening 11 which permits water, resulting from the melting of the ice, to flow into a basin 12 formed in the bottom of the cabinet from which the water may be removed through an outlet faucet 13.

Mounted between the partitions 8 are a series of shelves 14 each of which is secured to and supported by the inner shell 6 of the partitions 8. The shelves are appreciably 60 spaced so as to accommodate drawers 15 therebetween. One drawer is mounted on each shelf and is so constructed that it does not come in contact with the shelf which supports it or with any part of the cabinet. This is 65 accomplished by having the outer shell of the cabinet extended beyond the inner faces of the partitions 8, as indicated at 16, so that when the drawer is inserted it is held midway between the partitions 8. Furthermore, the 70 front of each drawer is provided with a panel 17 which limits inward movement of the drawer preventing contact of the inner end of the drawer with the shell 6. In addition the bottom of each drawer is equipped with supporting feet 18. The feet 18 are preferably 75 of V shape construction so that the drawers will freely slide on the shelves. If desired, each drawer may be equipped with a suitable handle 19 in order to facilitate operation 80 of the drawer.

In use of this device the ice, or other cooling agent, is packed in the compartments 9 and the butter chips placed in the drawers 15. The drawers are inserted in the cabinet in the 85 manner above set forth and the panels 17 thereof are so formed that they not only limit inward movement of the drawers but in addition act as an air seal when the drawers are in a closed position, as illustrated in Fig. 3. 90 The sides of the drawers are frictionally engaged by the extended portions 16 of the outer shell of the cabinet not only to space the drawers from the partitions 8, as above set forth, but also to make an air tight connection 95 as far as possible. By this construction, air is permitted to constantly circulate completely around the drawers and the butter is preserved in the desired state of refrigeration and protected from contamination by dirt, 100 vermin or the like.

It is apparent that numerous changes may be made in this device within the scope of the appended claims.

What is claimed is:—

1. A butter refrigerator including inner and outer shells equipped with an interposed

heat insulating material, said shells having registering openings in one side thereof, partitions mounted in the inner shell each of which impinges against the rear wall of the inner shell and projects forwardly into engagement with the outer shell near the opening of the latter, the margins of said outer shell extending beyond the inner faces of said partitions, shelves mounted between said partitions, and drawers slidably mounted on the shelves having the sides thereof engaged with the marginal edges of the outer shell, at the opening of the latter, to space the sides of the drawers from the partition.

15 2. A butter refrigerator including inner and outer shells equipped with an interposed heat insulating material, said shells having registering openings in one side thereof, partitions mounted in the inner shell, one margin of each of which is engaged with the inner face of the inner shell and the opposite margin engaged with the inner face of the outer

shell near the opening of the latter, the margins of said outer shell extending beyond the inner faces of said partitions, said partitions abutting the marginal edge of the inner shell at the opening of the latter to provide ice-receiving compartments between the partitions and inner shell, shelves mounted between and snugly engaged with the inner shell and partitions, drawers slidably mounted on said shelves, the outer faces of the sides of which engage the margins of the outer shell at the opening of the latter to space the sides of the drawers from the partitions, the lowermost shelf being spaced from the bottom of the inner shell to provide a compartment communicating with the ice compartments to permit the passage of water from the ice compartments into the compartment beneath the lowest shelf.

In testimony whereof I have signed my name to this specification.

JOHN DEMETRIUS POLETIS.
